UNITED STATES PATENT OFFICE.

WILLIAM B. FOSTER, OF CINCINNATI, OHIO, ASSIGNOR TO UNION SPECIAL MACHINE COMPANY, OF CHICAGO, ILLINOIS, A CORPORATION OF ILLINOIS.

WAISTBAND FOR TROUSERS.

Application filed January 5, 1925. Serial No. 584.

The invention relates to new and useful improvements in trousers, and more particularly to the waist band construction thereof.

5 An object of the invention is to provide a waist band which includes a stiffening strip and a lining or facing strip, wherein the lining strip and stiffening strip are secured together and to the body fabric forming the trousers by stitches which are concealed from view at the front of the garment by the body fabric, and also concealed from view at the inside of the garment by the facing strip, and wherein there are two lines of concealed stitches, one of which is located adjacent the upper edge of the stiffening strip and the other adjacent the lower edge of the stiffening strip, and wherein the facing strip of the waist band is wider than 15 the stiffening strip and projects below the same when the parts are united.

In the drawings which show by way of illustration one embodiment of the invention—

25 Figure 1 is a sectional view through the body fabric of the trousers, the stiffening strip and the facing strip which have been united by my improved arrangement of concealed stitches, and prior to the folding of 30 the waist band inside the garment;

Figure 2 is a similar view, but showing the waist band structure folded inside of the body fabric of the trousers, and

35 Figure 3 is a plan view from the inside of the garment, the several layers being broken away to show the construction of the waist band.

Referring to the drawings, the waist band consists of a canvas stiffening strip 1. The 40 body fabric of the trousers is indicated at 2, and the facing strip for the waist band is indicated at 3. This facing strip is considerably wider than the stiffening strip. One edge of the facing strip is inturned at 45 4, and this inturned edge is superposed upon the body portion of the fabric forming the trousers, and the body portion 2 is superposed upon the canvas strip 1. These parts are united by a line of stitches 5 which 50 enter first the inturned portion of the facing strip and emerge from the outer face of the stiffening strip where the thread loops forming the penetrating stitches are secured in the ordinary way; that is, either by a 55 looper thread or interlocking of the loops

which penetrate the fabric parts. The lower edge of the facing strip 3 is inturned at 6. This inturned portion 6 is of considerable length so that the fold in the facing strip extends some distance below the edge 8 of the stiffening strip. The folded edge of the facing strip is indicated at 7. The inturned portion 6 of the facing strip is secured to the stiffening strip 1 by a line of 60 stitches 9. These stitches are formed by a series of loops which pass first through the inturned portion 6 of the facing strip and then through the stiffening strip, and the loops are then enchain or secured by the looper thread. These concealed stitches are 65 of the type shown in the patent to Higgins No. 1,195,814, granted August 22, 1916. The thread from which the loops are formed lies between the inturned portions of the facing strip and the body portion of the facing 70 strip, and the loops are passed through said inturned portions and through the fabric parts to be united thereby. Thus it is that the body portion of the facing will conceal 75 the threads so that they are invisible from the face side of the fabric strip. The body fabric, where it has been secured to the waist band is folded to the position shown in Fig. 2, and the stitched parts may be tacked in this position, if desired. The body fabric 80 85 90 95 100 105 110

2 will conceal the enchain loops which lock the needle threads and cause the loops formed therein to secure the parts together. The body portion of the facing strip will likewise conceal the threads from which the loops are formed for stitching the parts as described above.

I do not claim broadly a waist band construction wherein the threads for securing the parts are concealed as above noted, but I do believe that I am the first to provide a waist band structure having the parts there- 100

of secured together by concealed stitches and wherein the waist band is sufficiently wide to hang below the lower edge of the stiffening strip so as to conceal said edge.

In a co-pending application filed of even date herewith, Serial No. 570, there is shown a machine for forming the waist band which is described above. The broad principle em- 105 bodied in said machine resides in the fact that the facing strip passes to the stitching point through a point in rear of the needles and the side edges of the facing strip are folded around the needles so that when the 110

facing strip is caused to move rearwardly away from the needles after the manner described in the Higgins patent, the inturned edges of the facing strip only will be penetrated by the needles.

From the above it will be apparent that a waist band construction has been provided which can be made and secured to the body portion of trousers in one operation, both the upper and lower edges of the waist band being finished and the parts which are united during this operation have their stitches laid so as to be concealed from the front of the body fabric as well as from the inner face.

It is obvious that minor changes in the details of construction and the arrangement of the parts may be made without departing from the spirit of the invention as set forth in the appended claim.

Having thus described the invention, what I claim as new and desire to secure by Letters-Patent, is—

The combination with the body fabric of trousers, of a stiffening strip at the waist band of the trousers, said body fabric being folded over the upper edge of said stiffening

strip, a facing strip having its upper edge inturned and placed against the inner face of the folded over edge of the body fabric, a line of stitches passing through the inturned portion only of the facing, said folded over edge of the body fabric and the stiffening strip, and concealed from view at the outer face of the garment by the body fabric, and at the inner face of the garment by said facing strip, said facing strip at the lower edge thereof being inturned and secured to the stiffening strip by a line of stitches which passes through the inturned portion only of the facing strip and through said stiffening strip, said last-named line of stitches being concealed from view at the outer face of the garment by the body fabric, and at the inner face of the garment by said facing strip, said facing strip having a fold in the upper edge thereof substantially in alinement with the upper edge of the stiffening strip and its fold in the lower edge thereof disposed at a considerable distance below the lower edge of the stiffening strip.

In testimony whereof, I affix my signature.

WILLIAM B. FOSTER.
